UNITED STATES PATENT OFFICE.

MICHAEL ZIER, OF NEW ALBANY, INDIANA.

VERTICAL BOILER.

SPECIFICATION forming part of Letters Patent No. 585,898, dated July 6, 1897.

Application filed March 8, 1897. Serial No. 626,400. (No model.)

To all whom it may concern:

Be it known that I, MICHAEL ZIER, a citizen of the United States, residing at New Albany, in the county of Floyd and State of Indiana, have invented certain new and useful Improvements in Vertical Boilers; and I do hereby declare the following to be a full, clear, and exact description of the invention, such as will enable others skilled in the art to 10 which it appertains to make and use the same.

My invention relates particularly to vertical boilers, and has for its object to improve the construction of the same, with a view of obtaining the greatest possible amount of 15 heat-radiating surface exposed to the water-containing compartments, thus obtaining the greatest economy and rapidity in the steam-generating action.

To the ends above noted my invention consists of the novel devices and combinations of devices hereinafter described, and defined in the claims.

The preferred form of my invention and also a modification of the same are illustrated 25 in the accompanying drawings, wherein, like characters indicating like parts throughout the several views—

Figure 1 is a view, principally in transverse vertical section, taken centrally through the 30 preferred form of my improved boiler and stack connection therefrom, but with some parts shown in full. Fig. 2 is a horizontal section taken substantially on the line X² X² of Fig. 1. Fig. 3 is a vertical section through 35 the boiler, taken on the line X³ X³ of Fig. 1. Fig. 4 is a horizontal section taken on the line X⁴ X⁴ of Fig. 3. Fig. 5 is a horizontal section taken on the line X⁵ X⁵ of Fig. 3; and Fig. 6 is a central vertical section through a 40 portion of a boiler which in its main features of construction is similar to that of my preferred form, but is modified in certain details, some parts of said boiler being broken away.

45 'a indicates a fire-box, which, as shown, is cylindrical in form, is closed at its upper end by a flue-sheet a', is provided with an ordinary grate a², and projects below said grate to form an ash pit or chamber a³. Preferably the fire-box a is supported by a small brick foundation e. The combustion-cham-

ber proper is located a considerable distance above the fire-box a and is in communication therewith through vertical draft flues or tubes. Preferably this combustion-chamber 55 is in the form of a truncated conical vessel a⁴, positioned small end upward, with its larger lower end in communication with the fire-box a through the series of vertical flues a⁵. The small upper end of the conical combustion-chamber a⁴ is closed by means of a removable dome-like head a⁶. A fusible plug a⁷ is screw-threaded through a suitable seat in the cap a⁶, for a purpose which will herein-after appear.

b indicates a thin metallic case or shell which surrounds and incloses the fire-box a, the flues a⁵, and the combustion-chamber a⁴. As shown, the main body of this case or shell b is cylindrical in form, while the base of the 70 same flares slightly, and its upper portion is reduced on a taper, so as to run approximately parallel to the walls of the combustion-chamber a⁴, thus forming a water-jacketing chamber around the said parts a, a⁴, and a⁵.

Secured to and opening from the upper end of the water-jacketing case b is an expanded drum-like shell b', which constitutes what I may term the "steam-chamber." The upper head of the drum or steam-chamber b' 80 is provided with a centrally-located manhole, which is normally closed by means of an ordinary manhole-cover and clamp b² b³. As shown, said drum b' is also provided with a hand-hole in one side, which is normally closed by means of a removable cover b⁴ and clamp b⁵. The shell or case b is also shown as provided with several laterally-opening hand-holes, which are normally closed by means of removable covers b⁶ and clamps b⁷. 85 The fuel is introduced into the fire-box a through a door-opening formed through a thimble-like casting b⁸, which is secured with water-tight joints between said shell b and the shell of said fire-box a. The opening 90 through this thimble b⁸ is adapted to be opened and closed by means of an ordinary hinged door b⁹. Rigidly secured within the cylindrical portion of the shell b a slight distance above the flue-sheet a' is a conical deflector b¹⁰, the periphery of which terminates short of the walls of said shell b and is secured

thereto by means of bracket-irons b^{11} . All of the draft or fire flues a^5 pass through this conical deflector b^{10} . Preferably the apex or center of the conical deflector b^{10} is perforated 5 or cut away, as shown at b^{12} , to permit the free circulation of the water contained in the shell or casing b under the action of convection, as will later more fully appear.

The steam is drawn off from the steam-chamber b' through a pipe c , which terminates within said steam-chamber in an annular finely-perforated nozzle or receiving-section c' .

A multiplicity of short pipe-sections a^8 15 open through the parallel wall portions of the conical combustion-chamber a^4 and shell or casing b .

A cylindrical double-walled water-jacketing chamber f is spaced apart from and secured around the cylindrical and conical portions of the shell b and the lower portion of the drum b' , so as to form a supplemental or secondary combustion-chamber g between said water-jacket f and said parts b and b' .

25 The lower extremities of the water-jacket f and of the supplemental combustion-chamber g are tightly closed by means of annular bottom pieces f' and g' , respectively. The upper extremities of the walls of the water-jacket f are pressed together and secured with a steam-tight joint, and the annular opening between the same and the exterior of the drum b' is tightly closed by means of an annular top g^2 , which may be made of 35 any suitable material, but is preferably constructed of fire-clay. The annular bottom g' of the supplemental combustion-chamber is provided with a series of hand openings or holes which are normally tightly closed by 40 means of removable plugs or covers g^3 .

Between the lower portion of the water-jacketing chamber f and the interior of the cylindrical portion of the case or shell b a series of short radial pipes f^2 open communication, and in like manner between the upper portion of said water-jacketing chamber f and the interior of the steam-chamber or drum b' a series of radial pipe-sections f^3 open communication. As shown, the outer shell of the 45 water-jacketing chamber f is perforated or provided with a hand-hole in line with each of the pipe-sections f^2 and f^3 , which hand-holes are normally closed by means of removable plugs or covers f^4 and clamps f^5 . As 55 shown, the water-jacketing chamber f is also provided with a pair of diametrically opposite manholes f^6 , which are normally tightly closed by means of removable covers f^7 . Access is also afforded to the interior of the combustion-chamber a^4 through a suitable man-hole formed in a horizontal tube or thimble section f^8 , which forms an opening through both walls of said water-jacket f , through the shell b , and through the shell of said chamber a^4 . 65 Normally the outer extremity of the manhole or thimble section f^8 is tightly closed by means of a removable cover f^9 . By reference to

Fig. 1 it will be noted that the shell or casing b is provided with a laterally-projecting thimble portion b^{13} , which is spaced apart from and surrounds the thimble-section f^8 .

The products of combustion are drawn from the supplemental combustion-chamber g through a double-walled thimble portion f^{10} , which opens laterally through the lower portion of one side of the water-jacketing chamber f and opens into a lateral extension k of a smoke-stack k' . This smoke-stack forms no part of my invention and may be of any suitable construction. As shown, it is provided with a damper k^2 above the lateral projection k and with a door k^3 below the same.

p and p' indicate a pair of blow-off pipes which open into the bottom of the annular water-chamber formed between the base of 85 the shell b and the exterior of the fire-box a . As shown, these pipes p and p' open at points diametrically opposite to each other, and one of the same is either in communication or adapted for communication with a source of 90 steam-supply under pressure, while the other of said pipes extends to some suitable point of exhaust. Both of the said pipes should be provided with valves. (Not shown.)

In the construction illustrated in Fig. 6 the 95 details of the boiler are substantially identical with the construction above described, with the following exceptions: The smoke-stack (shown at r) has its base secured directly on the top of the drum or steam-chamber b' . Steam is drawn off from the steam-chamber b' through a pipe r' , which opens through the central portion of the upper head of said chamber or drum b' and extends horizontally through the stack r . Water communication between the interior of the chamber or drum b' and the upper portion of the annular water-jacketing chamber f is afforded through an elbow-pipe t , while water communication is in a similar manner afforded between the lower portion of said water-jacketing chamber f and the interior of the shell or casing b through an elbow-pipe t' , and the products of combustion from the secondary or supplemental combustion-chamber g pass 105 directly to the face of the stack r through a multiplicity of vertical fire-flues w , which are passed through the steam-chamber or drum b' . In this construction the products of combustion in passing through the flues w serve 110 to superheat the steam within said steam-chamber. y indicates water contained in the water-jacketing chamber f , the shell or case b , and the lower portion of the drum or steam-chamber b' . This column of water should 115 be kept at substantially the altitude illustrated in Figs. 1 and 3, and should always be kept above the radial pipe-sections f^3 and the fusible plug a^7 in the top of the combustion-chamber a^4 . A suitable water-gage (not 120 shown) may be employed for indicating the altitude of this column of water. Preferably the exterior of the water-jacketing chamber f should be provided with a covering or jacket

of asbestos, wood, or other suitable heat-insulating material (not shown) for preventing the radiation and waste of heat.

The action of the above-described boiler is substantially as follows: The combustion will of course commence in the fire-box *a*, from whence the products of combustion will pass upward through the vertical fire-flues *a*⁵ into the main combustion-chamber *a*⁴. Within the combustion-chamber *a*⁴ the finely-divided ignited streams of the combustible gases will be reunited and commingled together, thus greatly intensifying the combustion within this chamber. From the combustion-chamber *a*⁴ the combustible gases, which by this time have been nearly but not completely consumed, pass outward through the radial pipe-sections *a*⁸ into the secondary or supplemental combustion-chamber *g*. In the form of the device illustrated in Figs. 1 to 5, inclusive, the products of combustion within the supplemental combustion-chamber *g* are subjected to a downdraft, and, after circulating within said supplemental chamber, are drawn off through the lateral extensions *f*¹⁰ and *k* and through the smoke-stack *k'*.

As already indicated in the construction illustrated in Fig. 6, the products of combustion are drawn from the supplemental combustion-chamber *g* through the vertical pipe-section *w* in the steam-chamber *b'* into the stack *r*.

In both of the constructions above described it is obvious that an extremely large amount of heat-radiating surface is exposed to the water which is to be heated or converted into steam and that the said water is distributed or exposed to these heat-radiating surfaces in very thin columns or sheets. It is also thought to be evident that in virtue of this construction the water will be very rapidly heated and converted into steam and that the maximum heating efficiency of the fuel is thereby effected, thereby giving an extremely economical and efficient boiler. The water which is thus heated is free to circulate from the various water-containing compartments or vessels through the radial pipe-sections *f*² and *f*³ under the action of convection.

The impurities or sediment from the water contained in the shell or case *b* will fall onto the conical deflector *b*¹⁰, by which they will be deflected and caused to fall into the annular compartment formed around the exterior of the fire-box *a*. By this means the sediment is prevented from falling onto the flue-sheet *a'*, which is exposed to the direct action of heat. If allowed to fall onto this flue-sheet, the sediment would tend to burn or adhere thereto, which would obviously be very objectionable.

If by any reason the water should be allowed to lower below the fusible plug *a*⁷, this plug will readily melt, thus permitting the escape of steam into the combustion-chamber

*a*⁴, and from thence both into the fire-box and out through the smoke-stack. The steam which is discharged into the fire-box will tend to put the fire out, while all of the steam which escapes through the opening formed by the melting of the plug *a*⁷ will reduce the steam-pressure and prevent an explosion.

It will be understood, of course, that the specific details of construction above described may be considerably deviated from without departing from the spirit of my invention.

What I claim, and desire to secure by Letters Patent of the United States, is as follows:

1. A boiler comprising a primary combustion-chamber, a water-jacketing chamber incasing said primary combustion-chamber, a secondary or supplemental combustion-chamber surrounding said water-jacketing chamber and in communication with said primary combustion-chamber, and an exterior water-jacketing chamber surrounding said secondary combustion-chamber and in communication with the aforesaid water-jacketing chamber, substantially as described.

2. A boiler comprising a primary combustion-chamber, a water-jacketing chamber incasing said primary combustion-chamber and terminating above the same in a steam-chamber, a secondary or supplemental combustion-chamber surrounding said water-jacketing chamber and in communication with said primary combustion-chamber, and an exterior water-jacketing chamber surrounding said secondary combustion-chamber and in communication with the aforesaid water-jacketing chamber, substantially as described.

3. In a vertical boiler, the combination with a fire-box, of a primary combustion-chamber positioned above the same and in communication therewith, through a multiplicity of vertical draft-flues, a water-jacketing chamber incasing said parts and terminating at its upper end in a steam-chamber, a secondary or supplemental combustion-chamber surrounding said water-jacketing chamber and in communication with said primary combustion-chamber, and an exterior water-jacketing chamber surrounding said secondary combustion-chamber and in communication with the aforesaid water-jacketing chamber, substantially as described.

4. In a vertical boiler, the combination with a fire-box, of a combustion-chamber positioned above the same and in communication therewith through a multiplicity of vertical flues, a water-jacketing chamber surrounding said parts and extended at its upper end to form a steam chest or chamber, a secondary or supplemental combustion-chamber surrounding portions of said water-jacketing chamber and steam-chest, communicating passages between said combustion-chambers, an exterior water-jacketing chamber surrounding said supplemental combustion-chamber, and communicating passages between said exterior water-jacketing cham-

ber and said steam-chamber and inside wa-
ter-jacketing chamber, substantially as de-
scribed.

5. In a vertical boiler, the combination with
a fire-box and vertical draft-flues rising
therefrom, of the conical deflector b^{10} , sub-
merged within the boiler and supported above
the flue-sheet thereof, substantially as and
for the purposes set forth.
- 10 6. In a vertical boiler, the combination with
a fire-box and vertical draft-flues rising

therefrom, of the conical deflector b^{10} sup-
ported above the flue-sheet thereof and pro-
vided at its center or apex with the perfora-
tion b^{12} , substantially as and for the purposes
set forth.

In testimony whereof I affix my signature
in presence of two witnesses.

MICHAEL ZIER.

Witnesses:

LAFAYETTE FREDERICK,
JACOB ROTHWEILER.
